Filed Oct. 21, 1966, Ser. No. 4,360

Term of patent 14 years

(Cl. D54—12)

FIG. 1

FIG. 2

FIG. 3

FIG. 4

FIG. 5

FIG. 1 is a front elevation of a fork or similar article showing my new design;

FIG. 2 is a rear elevation thereof;

FIG. 3 is a side elevation thereof;

FIG. 4 is an end view thereof; and

FIG. 5 is an enlarged cross-section taken on line 5—5 of FIG. 1.

The essential features of my design reside in the configuration of the handle in combination with the particular type of ornamentation as applied thereto, the dominant feature of the design residing in the handle shown in full lines, the conventional tines being shown in broken lines.

The design is intended for use on sets comprising forks, knives and similar articles.

I claim:

The ornamental design for a fork or similar article, substantially as shown and described.
